UNITED STATES PATENT OFFICE

JOHN YOUNG, OF YOKER, GLASGOW, SCOTLAND, ASSIGNOR TO DRYSDALE AND COMPANY, LIMITED, OF GLASGOW, SCOTLAND

COMBINED WATER AND AIR PUMP UNIT

Application filed March 11, 1931, Serial No. 521,775, and in Great Britain March 14, 1930.

The present invention relates to pumping units including a water pump and an air pump. Units according to the invention are especially intended for use in vacuum steam heating installations.

In steam heating installations it is common practice to return the condensed steam to a receiver which is maintained at a vacuum, and to withdraw air from this receiver by an air pump and the condensate by a water-extraction pump. The air and water are sometimes however withdrawn by one and the same pump. The condensate may be raised in pressure by the pump which withdraws it to a value sufficient to return it to a hot well at atmospheric pressure or to the heating steam boiler (which works at a suitable pressure).

The present invention consists in a construction and arrangement of pumping unit adapted to deal with the condensed steam and accompanying air of a vacuum steam heating installation. The unit includes a centrifugal water-extraction pump, a rotary "water-ring" dry air pump, a receiver for the condensate with accompanying air, and connections and accessories as are necessary or desirable. The invention will be defined in the annexed claims, but it may here be said—to give a clear idea of the nature of the invention—that the characteristic features of the invention are:—

(1) The water pump impeller and the air pump rotor are carried on a vertical spindle—the same spindle: The water pump impeller is arranged below the air pump rotor: The admission to the water pump impeller is at the top thereof: The admission to the air pump rotor is at the top thereof.

(2) The pump casing is closed at the bottom: There is no spindle gland there.

(3) A bearing is provided for the spindle between the water pump impeller and the air pump rotor, and another bearing outside and above the pump casing.

(4) The electric motor or other driving means is above the pump proper.

(5) The receiver structure has its greatest dimension vertical: It is arranged alongside the pump casing and fixed (e. g. by bolts)

thereto: It comprises a main chamber and a supplementary chamber above it: A float-controlled valve is provided in the supplementary chamber: This valve controls the flow of water from the supplementary chamber to the main chamber. 55

(6) The air-suction pipe for the air pump from the top of the main chamber of the receiver, the air-discharge pipe from the air pump to the supplementary chamber, and the sealing water supply pipe to the air pump all pass through the main chamber of the receiver: They communicate with the pump casing at the place where the receiver structure is connected to the pump casing. 60 65

For clearness and to prevent misunderstanding it will here be explained that by a pump of the rotary "water-ring" type is meant a pump in which the rotor rotates in a chamber generally of circular section eccentric to the axis of the rotor. The rotor is formed or provided with radiating vanes. Water (or other liquid) is held within the air-pump chamber. By the tractive action of the rotor vanes this water rotates within the casing; it tends to follow the contour of the chamber; and it is of such amount that in part of the casing it does not (when the pump is in action) extend inwards as far as the roots of the vanes, so that spaces are left between contiguous vanes and the enveloping water. Suitable air admission and air discharge ports are provided whereby air is admitted to these inter-vane spaces where they are increasing in capacity, and discharged therefrom where they are contracting, the action being well known. 70 75 80 85

The accompanying drawings illustrate the carrying of the invention into effect in one convenient manner. 90

Fig. 1 is a vertical section through the machine. 95

Fig. 2 is an end elevation of the machine. Fig. 3 is a plan of the pump structure with the driving motor and the support for it removed.

The air and water pumps are arranged in the same casing *a*. The water pump impeller *c* and the air pump rotor *d* are carried by the same spindle *b*. This spindle is vertical. It 100

will be seen that the water-extraction impeller is located below the water-ring air pump rotor. *e* is the suction port of the water pump and 15 the water admission passage to the impeller of the same. This passage, it will be seen, leads to the top of the impeller. *f* is the suction port to the rotor of the air pump and 16 the admission passage to this rotor. This admission passage, it will be seen, leads to the top of the rotor.

10 The spindle *b* terminates just below the water-extraction impeller: There is no stuffing box or opening in the casing *a* at the bottom thereof. A bearing *h* is provided for 15 the spindle between the water-extraction impeller and the air pump rotor. The spindle passes out of the casing through a stuffing box *k*. Another bearing *m* is provided for the spindle above the stuffing box. Above 20 this bearing *m* the spindle is coupled, at 16, to the shaft of the driving means.

25 The driving means in the present instance consists of an electric motor *n*. The pump casing is provided with an upward extension *o* furnished with a flange *p* to which the motor is bolted.

30 The receiver for the condensate is in a receiver structure *g* of which the greatest dimension is vertical. It is supported from the pump casing and is rigidly connected thereto, e. g. by bolts. This structure (in the present example of the execution of the invention) encloses a main chamber *r* and a chamber above it, which will be called the supplementary chamber. The receiver structure is (in 35 the present example) of cylindrical form with vertical axis and with a domed top.

40 In the supplementary chamber is a float *v* which controls a needle valve *w* which in turn controls a passage *x* leading from the supplementary chamber to the receiving chamber. *z* is a vent for discharging the air delivered by the air pump to atmosphere. This vent is provided with a non-return valve 45 when the pump is controlled by an automatic float or vacuum-operated switch.

45 The connections between the receiver structure and the pump casing are four in number.

50 1. The water admission port 2 from the receiver chamber to the water-extraction pump suction *e*. This port 2 is located near the bottom but not precisely at the bottom of the receiver chamber. The portion 3 of 55 the receiver chamber below the port acts as a sump or trap for collecting sludge and other material liable to damage the pump.

55 2. A stand pipe 4 within the receiver chamber and extending through the same, the upper end opening, at 5 into that chamber at the top thereof while the lower end of the pipe is connected to the suction port *f* of the air pump in the pump casing.

60 3. A pipe 6 for the air pump discharge. This pipe is connected at its lower end to

the air pump delivery port 17 in the pump structure: Its upper end opens into the supplementary chamber. This pipe passes through the receiver chamber without communicating with it. (The air is discharged 70 to atmosphere through the air vent *z*).

75 4. A pipe 7 for supplying the sealing water to the water-ring pump. This pipe 7 also passes through the receiver chamber without communicating with it. Its upper end opens into the supplementary chamber while the lower end is connected by the passage 18 to the air pump suction in the pump casing.

80 The electric motor *n* employed in the present example is controlled by a float 10 located in the receiver chamber. A rod 11 from this float (in the present construction) passes centrally upwards through the receiver chamber and supplementary chamber to a switch device 12 at the top of the latter chamber (outside the receiver structure) which device controls the electric motor. No novelty is claimed for this switch device. It is of known construction. It functions such that the motor starts when the water level in the receiver chamber reaches a pre-determined height and stops when the water falls again to a pre-determined level.

85 The switch instead of, or in addition to being actuated by a float, may be operated by means of a spring-loaded diaphragm, which automatically cuts in the motor starter when the vacuum in the receiver has fallen below a pre-determined value.

90 The water-extraction pump is arranged 100 with delivery ports 13, 14 on either side so that the unit is "without hand"; that is, it can be fitted to left or right hand pipe arrangements.

95 The driving means may be other than an electric motor. A steam turbine might be employed with advantage in some cases.

100 The construction according to the present invention, by the free support of the motor on an upward extension piece of the pump casing avoids any chance of malalignment between motor and pump caused by expansion in the hot pipe returns or otherwise. The vertical disposition of pump and receiver structures allows of the apparatus occupying minimum space. The carrying of the pipes 4, 6, and 7 through the receiver, as described, avoids air leakage; and the number of joints exposed to atmosphere is reduced to a minimum. The base area being small, the loss of heat by contact area to the floor is reduced to a minimum, and loss of heat is also reduced by the elimination of outside pipes. The construction is conducive to the application of lagging in a simple manner.

105 Having thus described my invention, what I claim as new and desire to secure by Letters Patent is:

110 A combined water and air pump unit comprising in combination, a single casing

for the water pump and the air pump, a spindle passing vertically through this casing, the casing being closed below the lower end of the spindle, an impeller for the water pump within the said casing constructed for water-admission at its top, the impeller being mounted on the said spindle, a rotor for the air pump within the said casing constructed for air admission at its top, this rotor being mounted on the said spindle above the said impeller, a bearing for the spindle between the said impeller and the said rotor, a receiver structure separate from the said casing, said receiver structure comprising a main chamber, and a supplementary chamber above the said main chamber, a float-controlled valve in the said supplementary chamber arranged to control the flow therefrom into the said main chamber, an air-suction pipe for the air pump leading from the top of the said main chamber and connected to the air pump, an air-discharge pipe from the air pump discharging into the said supplementary chamber, a sealing-water-supply pipe leading from the said supplementary chamber and connected to the air pump.

2. A combined water and air pump unit comprising in combination, a single casing for the water pump and the air pump, a spindle passing vertically through this casing, the casing being closed below the lower end of the spindle, an impeller for the water pump within the said casing constructed for water-admission at its top, the impeller being mounted on the said spindle, a rotor for the air pump within the said casing constructed for air admission at its top, this rotor being mounted on the said spindle above the said impeller, a bearing for the spindle between the said impeller and the said rotor, a receiver structure separate from the said casing, said receiver structure comprising a main chamber, and a supplementary chamber above the said main chamber, a float-controlled valve in the said supplementary chamber arranged to control the flow therefrom into the said main chamber, an air-suction pipe for the air pump leading from the top of the said main chamber and extending downwards through the whole length of the said chamber and connected to the air pump, an air-discharge pipe from the air pump extending upwards through the whole length of the said main chamber and discharging into the said supplementary chamber, a sealing-water-supply pipe leading from the said supplementary chamber and connected to the air pump.

3. A combined water and air pump unit comprising in combination, a single casing for the water pump and the air pump, a spindle passing vertically through this casing, the casing being closed below the lower end of the spindle, an impeller for the water

pump within the said casing constructed for water-admission at its top, the impeller being mounted on the said spindle, a rotor for the air pump within the said casing constructed for air admission at its top, this rotor being mounted on the said spindle above the said impeller, a bearing for the spindle between the said impeller and the said rotor, a receiver structure separate from the said casing, said receiver structure comprising a main chamber, and a supplementary chamber above the said main chamber, a float-controlled valve in the said supplementary chamber arranged to control the flow therefrom into the said main chamber, an air-suction pipe for the air pump leading from the top of the said main chamber and connected to the air pump, an air-discharge pipe from the air pump discharging into the said supplementary chamber, a sealing-water-supply pipe leading from the said supplementary chamber and connected to the air pump at the same place as the said air-suction pipe and the said air-discharge pipe.

4. A combined water and air pump unit comprising in combination, a single casing for the water pump and the air pump, a spindle passing vertically through this casing, the casing being closed below the lower end of the spindle, an impeller for the water pump within the said casing constructed for water-admission at its top, the impeller being mounted on the said spindle, a rotor for the air pump within the said casing constructed for air admission at its top, this rotor being mounted on the said spindle above the said impeller, a bearing for the spindle between the said impeller and the said rotor, a receiver structure, of which the greatest dimension is vertical, separate from the said casing, said receiver structure comprising a main chamber, and a supplementary chamber above the said main chamber, a float-controlled valve in the said supplementary chamber arranged to control the flow therefrom into the said main chamber, an air-suction pipe for the air pump leading from the top of the said main chamber and connected to the air pump, an air-discharge pipe from the air pump discharging into the said supplementary chamber, a sealing-water-supply pipe leading from the said supplementary chamber and connected to the air pump.

5. A combined water and air pump unit comprising in combination, a single casing for the water pump and the air pump, a spindle passing vertically through this casing, the casing being closed below the lower end of the spindle, an impeller for the water pump within the said casing constructed for water-admission at its top, the impeller being mounted on the said spindle, a rotor for the air pump within the said casing constructed

- for air admission at its top, this rotor being mounted on the said spindle above the said impeller, a bearing for the spindle between the said impeller and the said rotor, a receiver structure, of which the greatest dimension is vertical, separate from the said casing, said receiver structure comprising a main chamber, and a supplementary chamber above the said main chamber, a float-controlled valve 5 in the said supplementary chamber arranged to control the flow therefrom into the said main chamber, an air-suction pipe for the air pump leading from the top of the said main chamber and extending downwards through 10 the whole length of the said chamber and connected to the air pump, an air-discharge pipe from the air pump extending upwards through the whole length of the said main chamber and discharging into the said supplementary chamber, a sealing-water-supply pipe leading from the said supplementary chamber and extending downwards through the whole length of the said main chamber and connected to the air pump.
- 15 6. A combined water and air pump unit comprising in combination, a single casing for the water pump and the air pump, a spindle passing vertically through this casing, the casing being closed below the lower end of the spindle, an impeller for the water pump within the said casing constructed for water-admission at its top, the impeller being mounted on the said spindle, a rotor for the air pump within the said casing constructed for air admission at its top, this rotor being mounted on the said spindle above the said impeller, a bearing for the spindle between the said impeller and the said rotor, driving means for the said spindle above the 20 said casing, a receiver structure separate from the said casing, said receiver structure comprising a main chamber, and a supplementary chamber above the said main chamber, a float-controlled valve in the said supplementary chamber arranged to control the flow therefrom into the said main chamber, an air-suction pipe for the air pump leading from the top of the said main chamber and connected to the air pump, an air-discharge pipe from the air pump discharging into the 25 said supplementary chamber, a sealing-water-supply pipe leading from the said supplementary chamber and connected to the air pump.
- 30 7. A combined water and air pump unit comprising in combination, a single casing for the water pump and the air pump, a spindle passing vertically through this casing, the casing being closed below the lower end of the spindle, an impeller for the water pump within the said casing constructed for water-admission at its top, the impeller being mounted on the said spindle, a rotor for the air pump within the said casing constructed for air admission at its top, this rotor being mounted on the said spindle above the said impeller, a bearing for the spindle between the said impeller and the said rotor, driving means for the said spindle above the 35 said casing, a receiver structure separate from the said casing, said receiver structure comprising a main chamber, and a supplementary chamber above the said main chamber, a float-controlled valve in the said supplementary chamber arranged to control the flow therefrom into the said main chamber, an air-suction pipe for the air pump leading from the top of the said main chamber and connected to the air pump, an air-discharge pipe from the air pump discharging into the 40 said supplementary chamber, a sealing-water-supply pipe leading from the said supplementary chamber and connected to the air pump.
- 45 8. A combined water and air pump unit comprising in combination, a single casing for the water pump and the air pump, a spindle passing vertically through this casing, the casing being closed below the lower end of the spindle, an impeller for the water pump within the said casing constructed for water-admission at its top, the impeller being mounted on the said spindle, a rotor for the air pump within the said casing constructed for air admission at its top, this rotor being mounted on the said spindle above the said impeller, a bearing for the spindle between the said impeller and the said rotor, driving means for the said spindle above the 50 said casing, a receiver structure separate from the said casing, said receiver structure comprising a main chamber, and a supplementary chamber above the said main chamber, a float-controlled valve in the said supplementary chamber arranged to control the flow therefrom into the said main chamber, an air-suction pipe for the air pump leading from the top of the said main chamber and connected to the air pump, an air-discharge pipe from the air pump discharging into the said supplementary chamber, a sealing-water-supply pipe leading from the said supplementary chamber and connected to the air pump.
- 55 9. I hereby sign my name to this specification.
JOHN YOUNG.
